UNITED STATES PATENT OFFICE

2,571,020

ANTISKID OVERSHOE

Herbert E. Earl, Sr., Roselle Park, N. J.

Application April 20, 1949, Serial No. 88,585

1 Claim. (Cl. 152—175)

1

This invention relates to anti-skid attachments for vehicle wheels.

An important object of the invention is to provide an attachment of the character stated which is not only constructed in a manner to prevent skidding in the direction of vehicle movement, but also, is adapted to prevent lateral skidding equally well.

Another important object is to provide a device of the character stated embodying novelly formed and arranged removable calks, these calks being arranged in a manner to prevent skidding as previously mentioned, and being additionally removable for the purpose of substitution of new calks for those which are worn, and also for the purpose of varying the calk arrangement to suit particular conditions.

Another important object is to provide an attachment of the character stated that is durable, will not damage the vehicle tires, will be held securely in position, and will be readily placed upon a tire or removed therefrom.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawings

Fig. 1 is a fragmentary view partly in side elevation and partly in longitudinal section, taken through one form of the invention.

Fig. 2 is a fragmentary view partly in top plan and partly in horizontal section.

Fig. 3 is a section on line 3—3 of Fig. 1.

Fig. 4 is an enlarged fragmentary longitudinal section through a means for connecting the ends of the attachment.

Fig. 5 is a fragmentary side elevation of another form of the invention.

Fig. 6 is an enlarged transverse section through the form of Fig. 5.

Fig. 7 is an enlarged side elevation of a locking means applied to both forms of the invention.

Fig. 8 is a top plan view of said locking means.

Referring to the drawings in detail, 5 designates a conventional vehicle tire and as an anti-skid attachment therefor I provide a molded rubber overshoe 6, in which are molded the transversely extended cross bars 7, spaced circumferentially of the overshoe and curved to fit the transverse curvature of the tire 5 as best seen in Fig. 3.

2

Each bar 7 is fitted with a plurality of calks spaced transversely of the tire, and the calks are of a special shape to increase traction, prevent forward skidding or rearward skidding, and to prevent lateral skidding to either side. Thus, each bar is equipped with a suitable number of conical calks 8, and each calk 8 is formed at the base of its conical head with a wrench receiving collar 9 from which extends a threaded shank 10 threadable in threaded opening 11 formed in the cross bar 7. The molded rubber overshoe 6 has recesses 12 registering with the openings 11 for passage of the threaded shanks.

Each cross bar additionally has a plurality of calks 14 having heads of inverted wedge shape, with the crests of said heads being extended transversely of the tire thus to prevent forward or rearward skidding of the vehicle. Like the calks 8, the calks 14 have wrench receiving collars and threaded shanks receivable in the threaded openings formed in the cross bar.

Each cross bar additionally is equipped with any suitable number of calks 14 that also have heads of inverted wedge shape, the heads of the calks 14 being extended, however, in the direction of vehicle movement.

Thus, the calks 14 are particularly adapted to prevent side slip. In this connection, it may be noted that all the calks, that is, the calks 8, 13 and 14 are all adapted to increase traction during normal movement of the vehicle, the pointed calks being particularly well adapted to dig into icy surfaces for this purpose and for the purpose of preventing skidding in any direction, while the wedge shaped calks cooperate at all times with the conical calks for the purpose of increasing traction, while at the same time supplementing the conical calks in the matter of preventing skidding to the side or forwardly, by reason of the particular shape in which wide surfaces are provided that will be disposed broadside to the direction of skidding movement.

I provide a novel means for connecting the ends of the molded rubber overshoe 6 for the purpose of securing it in position upon a vehicle tire, and said means is particularly adapted for the purpose of preventing snow or ice from wedging between the connected ends. To this end, I provide end cross bars 15 that primarily, serve the purpose of supporting calks exactly in the manner of the cross bars 7.

However, the cross bars 15 differ from the cross bars 7, in that the cross bars 15 are formed with longitudinally spaced fingers which slope downwardly as at 16 toward the bottom surface of the molded rubber overshoe, and then project

from the ends of the overshoe as at 17. The fingers 17 on one end of the overshoe mesh with the fingers 17 at the other end as best seen in Fig. 2, and extend into recesses formed in the inner or under surfaces of the ends of the overshoe.

Thus, a flexible connection is provided while yet making said connection almost wholly impervious to snow or ice which may try to wedge its way into the connection during normal movement of the vehicle on snowy and icy roads.

In this connection, for the purpose of permitting additional flexibility in the connection, I bevel the end walls of the overshoe as at 18' to provide a V-shaped recess permitting flexing of said ends relative to each other.

Molded into the opposite side edge portions of the overshoe are chains 18, and extending from one end of each chain is a link 19 that extends around a rivet or pivot bolt 20 extended transversely of one end of a channeled body 21 having an end recess 22 to permit relative pivotal movement between the link 19 and body 21.

Extended transversely of the other end of the body 21 is another rivet 23, and disposed immediately adjacent said rivet 23 is a locking recess 24. Between the locking recess 24 and the first-named end of the body 21, I form integrally on opposite sides of the channeled body the enlargements 25.

Pivoted upon the rivet 23 is channel member 26, having at one end the ears 27 through which the pivot bolt or rivet 23 passes, thus to provide a swingable mounting of said channel member 26 upon the body 21. Extending from the pivotally connected ends of the body 21 and member 26 are the spaced apart spring arms 28, having intermediate their ends the bosses 29, and having on their free ends the outwardly extended lugs 30.

It will be noted that the bosses 29 define recesses into which are placed links 31 extending from the other ends of the respective chains.

The operation of mounting the attachment upon a vehicle tire can now be readily understood. The attachment is simply positioned over the tire, in the regular manner, and after the fingers 17 mesh in the position illustrated in Fig. 2, the snap lock illustrated in Fig. 7, one of which is disposed on either side of the overshoe, is operated by placing the links 31 in the appropriate recesses, whereupon the arms 28 are swung under the body 21, that is, to the left in Fig. 7. The spring arms 28, will be sprung apart by the lugs 30 in passing said lugs, and will snap into position over the lugs, and in this position of the parts, the links 31 will move fully into the locking recesses 24, thus to securely lock the ends of the overshoe together, for normal operation of the vehicle with the overshoe attachment on the vehicle tires.

In Figs. 5 and 6 I have illustrated a modified form of the invention in which the chains 18 have extended between them the transversely

extended cross bars 32 equipped with the removable calks 8, 13 and 14.

Cross bar 32 is cushioned from the surface of the vehicle tire by means of a fibre cushion 33 or other resilient member, and the threaded openings in the cross bar extend fully therethrough, so that the calks are threaded against the cushion.

A flexible and permanent connection is provided between the ends of the cross bars 32 and the adjacent portions of the chains 18, and to this end, the ends of the cross bars 32 are formed into sleeves 34 that extend around the medial portions of U-shaped links 35 having at their 10 opposite ends the sleeves 36 extending around the chain links.

A snap lock as shown in Figs. 7 and 8 is again used for the purpose of connecting the ends of the chains, thus to securely mount the anti-skid 20 and traction attachment upon the vehicle tire.

It may be noted that in both forms of the invention, the basic organization is the same, each form of the invention including the circumferentially extended chains 18 on either side 25 of the vehicle tire, between which chains extend the cross bars equipped with removable calks 20 alternating in any suitable arrangement, and said calks being pointed, wedge-shaped, and threaded into spaced apart openings in the cross 30 bars for the purpose of completing the construction of the anti-skid attachment.

What is claimed is:

An anti-skid attachment for a vehicle wheel comprising a rubber overshoe formed to a length 35 to extend through the full outer circumference of a wheel and proportioned as to width to overlie the entire tread portion of said wheel; a plurality of spaced apart metal cross bars free of 40 connections to each other and spaced circumferentially of said overshoe, each cross bar being molded within said overshoe and extending transversely of the overshoe at right angles to the plane of the wheel, each cross bar being formed with a plurality of threaded openings spaced 45 from end to end of the cross bar, the overshoe having openings registering with said threaded openings; and metal calks projecting outwardly from said overshoe, each calk including a threaded shank extending into the overshoe 50 opening and threaded into one of the threaded openings of the cross bars.

HERBERT E. EARL, SR.
